UNITED STATES PATENT OFFICE.

GEORGE W. SCHILLING, OF PHILADELPHIA, PENNSYLVANIA.

SWING.

1,016,712.

Specification of Letters Patent.

Patented Feb. 6, 1912.

Application filed September 7, 1909. Serial No. 516,550.

To all whom it may concern:

Be it known that I, GEORGE W. SCHILLING, a citizen of the United States, residing in the city and county of Philadelphia, State 5 of Pennsylvania, have invented a new and useful Swing, of which the following is a specification.

The object of this invention is to devise a novel construction of a double power swing 10 which will start with very little motion and gradually attain a greater height.

A further object of my invention is to construct a power swing wherein the stroke of the swing may be regulated as desired by 15 the employment of a suitable clutch.

A further object is to devise a novel driving mechanism for a swing so that a slower movement will be imparted thereto at the ends of the stroke.

20 It further consists of novel means for controlling the swing and novel means for checking the movement thereof as desired.

To the above ends my present invention consists of a novel construction of a power 25 swing which is actuated by frictional driving means and wherein novel means are employed for controlling the movement of the same and also novel means for regulating the stroke of the swing.

30 It further consists of other novel features of construction, all as will be hereinafter fully set forth.

For the purpose of illustrating my invention, I have shown in the accompanying 35 drawings one form thereof which is at present preferred by me, since the same has been found in practice to give satisfactory and reliable results, although it is to be understood that the various instrumentalities of 40 which my invention consists can be variously arranged and organized and that my invention is not limited to the precise arrangement and organization of these instrumentalities as herein shown and de- 45 scribed.

Figure 1 represents a sectional elevation of a swing embodying my invention, the section being taken on line $x-x$, Fig. 5. Fig. 2 is a sectional view of a portion of Fig. 1. Fig. 3 represents a sectional view of a portion of Fig. 1, showing more clearly certain details of construction. Fig. 4 represents a side elevation of one of the friction cones to which the arms of the swing 50 are secured. Fig. 5 represents a sectional elevation of my device, certain parts there- 55

of being removed for the sake of clearness of illustration. Fig. 6 represents a section on line $y-y$, Fig. 5. Fig. 7 represents a sectional elevation of another embodiment 60 of my invention. Fig. 8 represents a side elevation in detached position of a brake member seen in Fig. 5. Fig. 9 represents a side elevation of another embodiment of driving gears which may be employed if de- 65 sired. Fig. 10 represents a side elevation in detached position of one of the friction cones.

Similar numerals of reference indicate corresponding parts in the figures. 70

Referring to the drawings:—1 designates a motor of any desired or conventional type, operatively connected in any desired manner with the driving mechanism of the swing, in the present instance, a belt 2 being 75 provided which is driven by the motor shaft and imparts motion to a pulley 3 mounted on a shaft 4 on which latter is mounted an elliptical or intermittent gear 5 which meshes with a similar gear 6 mounted on a 80 shaft 7. The gear 6 is provided with a slot 8 whereby a connecting rod 9 may be adjustably secured with respect to the slot 8 by means of a bolt or equivalent fastening device 10. One end of the connecting rod 9 85 is operatively connected with an arm 11 fixedly mounted on a shaft 12 journaled in brackets 13 carried by a cross bar 14 which latter is provided with the side supports 15.

The shaft 12 has mounted thereon four 90 male friction cones 16, 17, 18 and 19, the cones 18 and 19 being keyed to the shaft and provided with double arms 54 and 20, the outer ends of which are preferably enlarged and provided with apertures 21 as most 95 clearly seen in Fig. 3. The aperture 21 has preferably a differential diameter and is adapted to receive a plunger 22 which is provided with a head 23 in order to maintain the same in assembled position and against 100 the head 23 abuts a spring 24, the other end of which is in engagement with an adjustable plug 25 whereby the tension of the spring 24 may be varied as desired. The plunger 22 is preferably provided with an 105 enlarged contact head 26. Since the plunger in one arm is constructed in a similar manner to the plunger in the other arm, I have deemed it unnecessary to describe in detail both of these plungers and the manner 110 in which they are mounted. The friction cones 16 and 19 are fastened to the shaft 12

by means of key ways 27 in order that said cones may have longitudinal movement relative to the shaft.

28 designates the female friction cones 5 which are loosely mounted on the shaft 12, said cones being provided with brackets 29 to which the arms 30 are secured which latter form the supports for the swing 31 on which the seats are preferably arranged back 10 to back in order that the weight will be as near the center of the swing as practicable, although of course if desired, the seat may be arranged in any other suitable manner. In order to maintain the proper friction 15 between the co-acting cones, I provide springs 32 which are interposed between the cone 16 and block 33, keyed to the shaft 12 so as to have longitudinal movement thereon, the movement of the block 33 in one 20 direction being limited by means of adjusting screws 34 carried by one of the brackets 13.

35 designates a friction brake which is loosely mounted on the shaft 12 and is provided with a quadrant 36 which travels within a bracket 37 secured to the side supports 15 and provided with set screws 38, which engage a bearing plate 39 thereby imparting a desired friction against the quadrant 30 36, it being noted that the quadrant 36 is provided with laterally extending lugs or contact members 40 with which the arms of the swing co-act.

41 is a clutch member loosely mounted on 35 the shaft 12 and coacting with a clutch member 42 having longitudinal movement only relatively to said shaft, said clutch member 42 being provided with an arm 43 to which may be connected a cord, cable or other desired connection for actuating the clutch 40 while the swing is in motion.

In order to stop the swing, I provide a 45 brake, which, as most clearly seen in Fig. 6, comprises a friction disk 44 with which co- acts a friction member 45 suitably fulcrumed and having secured to one end a spring 46, the other end of which is attached to a suitable fixed point such as the cross bar 14 whereby the members of the brake are normally maintained out of engagement. The 50 member 45 is provided with a rod or cable 47 whereby the latter may be actuated when desired. When a high swing is not desired I provide a friction drive by mounting the 55 arms of the swing in a different manner as seen in Fig. 7, wherein I secure to the arms 30 of the swing a collar 48 which is provided with a friction bushing 49 of leather or other suitable material which engages with the 60 shaft 12 or an eccentric 50 thereon.

In the embodiment seen in Fig. 9, I have 65 shown a modified form of driving mechanism wherein I employ two gears 51 and 52, each of which is provided with a dwell 53, the connecting rod 9 being secured with

respect to the gear 52 in a similar manner to that already described with reference to Fig. 1.

The operation of my device will now be readily apparent and is as follows:—When the motor 1 is started, motion is imparted 70 to the gears 5 and 6 which are preferably constructed in such a manner as to give a slower movement at the ends of the stroke in order to allow the swing to reverse, it being seen by reference to Fig. 1 that this is accomplished by the elliptical or intermittent gears 5 and 6, while in the embodiment seen in Fig. 9 this is accomplished by the employment of the dwell 53. The gear 6 imparts motion to the connecting rod 9 thereby rocking the shaft 12 whereupon the friction cones or drums 16, 17, 18 and 19 75 impart motion to the friction cones 28 loosely mounted on the shaft and thereby to the swing. After attaining a medium height, the double arms 54 and 20 come into action, increasing the height of the swing and in order to prevent too much jar when the double arms are brought into action I provide the spring plungers 22.

My novel construction of automatic brake becomes operative owing to the contact of the arms on the swing with the members 40 of the quadrant 36, it being apparent that as the swing is in motion one of the arms when it reaches a certain height will contact with the contact member on one side of said arm and the upward movement of the swing will be retarded by the engagement of the friction plate 39 with the quadrant, it being understood that the quadrant 36 will be moved from its normal position and on the return movement of the swing the arm on the opposite side will engage 100 with the other contact member 40 and the upward movement of the swing in a reverse direction will be restricted by the frictional contact with the frictional members 39 against the quadrant 36 so that an automatic friction brake is provided which will prevent the swing from traveling to an undesired height, it being apparent that the friction of the members 39 against the quadrant 36 may be readily adjusted by means 105 of the adjusting members 38 provided therefor. When the motive power is shut off and it is desired to bring the swing to a stop the rod or cable 47 is actuated, thereby causing the engagement of the friction member 45 with the friction wheel 44 fast on the shaft 12 thereby bringing the shaft 12 gradually to its stationary position.

If the embodiment seen in Fig. 7 is employed it will be seen that this construction embodies the broad principle of my invention, namely the friction drive for the swing and at the same time by employing an eccentric on the shaft I vary the throw of the swing.

It will be apparent that in some cases the double arms 54 and 20 may be dispensed with in which case the swing will not travel as high and it will also be apparent that 5 the form and construction of the friction cones may be varied according to the conditions of each case. It will also be apparent that by means of the friction brake the travel of the swing will be retarded to the 10 desired extent and the friction of the cones may be readily adjusted by means of the set screws 34, as is apparent.

So far as I am aware I am the first in 15 the art to devise a swing which is provided with frictional means for driving the same and it will be apparent to those skilled in this art that by such a construction the swing itself may be stopped at any time without shutting off the motor or the driving mechanism so that people may get in and out of 20 the swing while the driving mechanism is continuously operating.

It will now be apparent that I have devised a novel and useful construction of a 25 swing which embodies the features of advantage enumerated as desirable in the statement of the invention and the above description, and while I have in the present instance shown and described a preferred embodiment thereof which has been 30 found in practice to give satisfactory and reliable results, it is to be understood that the same is susceptible of modification in various particulars without departing from 35 the spirit or scope of the invention or sacrificing any of its advantages.

Having thus described my invention, what I claim as new and desire to secure by Letters Patent, is:—

40 1. In a device of the character described, a shaft suitably mounted, members loosely mounted thereon, a swing having the arms thereof rigidly connected with said members, devices carried by said shaft, supporting said members, and having frictional engagement therewith, means for rocking said shaft, means for automatically increasing the angle through which the swing vibrates, and a friction device with which 45 the arms of the swing coact to automatically retard the movement thereof at predetermined times during its travel.

50 2. In a device of the character described, a shaft suitably mounted, members loosely mounted thereon, a swing having the arms thereof rigidly connected with said members, devices carried by said shaft, supporting said members, and having frictional engagement therewith, means for rocking said 55 shaft, and means carried by the friction devices on said shaft for increasing the angle through which the same vibrates when the latter attains a predetermined height.

55 3. In a device of the character described, a shaft suitably mounted, members loosely

mounted thereon, a swing having the arms thereof rigidly connected with said members, devices carried by said shaft, supporting said members, and having frictional engagement therewith, means for rocking said 70 shaft, and spring pressed plungers carried by said friction devices for increasing the angle through which the same vibrates when the latter attains a predetermined height.

4. In a device of the character described 75 a shaft suitably mounted, members loosely mounted thereon, a swing having the arms thereof rigidly connected with said members, devices carried by said shaft, supporting said members, and having frictional engagement 80 therewith, means for rocking said shaft, an arm loosely mounted on said shaft, stationary means frictionally engaging said arm, and stops carried by said arm co-acting with the swing arms to automatically retard 85 the movement of the swing.

5. In a device of the character described, a shaft suitably mounted, members loosely mounted thereon, a swing having the arms thereof rigidly connected with said members, means for automatically increasing the angle through which the swing vibrates, devices carried by said shaft, supporting said members, and having frictional engagement therewith, means for rocking said 90 shaft, an arm loosely mounted on said shaft, stationary means frictionally engaging said arm, stops carried by said arm and co-acting with the swing arms to automatically retard the movement of the swing, a friction 95 disk carried by said shaft, a manually actuated friction member adapted to co-act with said disk, and yielding means for normally maintaining said friction member in inoperative position.

105 6. In a device of the character described, a shaft, suitably mounted, members having cone shaped recesses in their sides loosely mounted on the shaft, devices non-rotatably mounted on the shaft and engaging the 110 cone shaped recesses of said members to support the latter and having frictional engagement therewith, means for rocking said shaft, and a friction device with which the arms of the swing coact to automatically 115 retard the movement thereof at predetermined times, and including a movable member co-acting with the arms of the swing, a friction member, and means for varying the engagement of the friction member with 120 the movable member.

7. In a swing, a shaft suitably mounted, friction members thereon, a swing secured to said members, friction cones co-acting with one of said friction members and non-rotatably mounted on said shaft and provided with depending arms, spring actuated plungers carried by said arms and co-acting with the swing to increase the angle through 125 which the spring vibrates, and a friction 130

cone with which the other side of one of said friction members co-acts.

8. In a swing, a shaft suitably mounted, friction members thereon, elliptical gears operatively connected with said shaft for driving the same, a swing secured to said members, friction cones co-acting with one of said friction members and non-rotatably mounted on said shaft and provided with depending arms, devices carried by said arms and co-acting with the swing to increase the height thereof, a friction cone co-acting with the other side of one of said members, and a friction brake comprising a member movably mounted and having contact devices on opposite sides of the spring arms and stationary devices in frictional engagement with such member.

9. In a swing, a shaft suitably mounted, means for rocking said shaft, a swing loosely mounted on said shaft, and devices on said shaft having frictional engagement with said swing, said devices including means actuated by said shaft and co-acting with said swing for increasing the angle through which the swing vibrates.

10. In a swing, a shaft suitably mounted, means for rocking said shaft, a swing loosely mounted on said shaft, devices on said shaft having automatic frictional engagement with said swing and serving as a support for the latter, said devices including means actuated by said shaft and co-acting with said swing for increasing the angle through which the swing vibrates, and means for varying the friction of said devices.

11. In a swing, a shaft suitably mounted, means for rocking said shaft, a swing loosely mounted on said shaft, devices on said shaft having automatic frictional engagement with said swing and serving as a support for the latter, means carried by said devices actuated by said shaft and co-acting with said swing for increasing the angle through which the swing vibrates, in combination with an automatic friction brake for said swing, and a manually actuated brake for said swing.

12. In a swing, a shaft suitably mounted, means for rocking said shaft, a swing having arms loosely mounted on said shaft, de-

vices on said shaft having frictional engagement with said swing, means actuated by said shaft and co-acting with said swing for increasing the angle through which the swing vibrates, in combination with a friction brake having contact members co-acting with said arms to limit the stroke of the swing.

13. In a swing, a shaft suitably mounted, means for rocking said shaft, a swing loosely mounted on said shaft, devices on said shaft having frictional engagement with said swing, means actuated by said shaft and co-acting with said swing for increasing the angle through which the swing vibrates, in combination with braking means for said swing.

14. In a swing, a shaft suitably mounted, means for rocking said shaft, a swing loosely mounted on said shaft, devices keyed on said shaft having frictional engagement with said swing, means actuated by said shaft and co-acting with said swing for increasing the angle through which the swing vibrates, in combination with an automatic friction brake for said swing, and means for varying the friction of said brake.

15. In a swing, a support, a shaft mounted thereon, a swing loosely mounted on said shaft, frictional devices intermediate said shaft and swing for actuating the latter, a member loosely mounted on said shaft, arms extending from said member and in the path of the swing, and means carried by said support and frictionally engaging said member to retard the movement thereof when said arms are engaged by the swing.

16. In a swing, the combination with a motor, of elliptical gears driven thereby, a shaft suitably mounted and operatively connected with said gears, friction devices carried by said shaft, and a swing engaging said friction devices and supported thereon, in combination with means carried by said friction devices for automatically increasing the angle through which the swing vibrates.

GEORGE W. SCHILLING.
